UNITED STATES PATENT OFFICE.

HARVEY SLATER, OF CHICAGO, ILLINOIS, ASSIGNOR TO CHARLES F. ELMES ENGINEERING WORKS, OF CHICAGO, ILLINOIS, A CORPORATION OF ILLINOIS.

PRESS.

Application filed January 27, 1919. Serial No. 273,350.

To all whom it may concern:

Be it known that I, HARVEY SLATER, a citizen of the United States, residing at Chicago, in the county of Cook and State 5 of Illinois, have invented certain new and useful Improvements in Presses, of which the following is a specification.

The present invention has particular reference to a press construction wherein provision is made for synchronizing the operation of a pressure-fluid-operated press proper and its automatically actuated control valve under all variations of speed, and for the control of the valve action by means 15 of a predetermined attained pressure in the press itself, whereby to insure at all times and under all conditions a uniformity of operation and resultant product.

While the novel features of the press 20 assemblage constituting the invention are susceptible of modification within a wide range to adapt the same to different types of presses, I have chosen to illustrate and describe the invention as embodied, by way 25 of example, in a quick-acting hydraulic press for forming articles from pulverized material, wherein it is important that the material shall be subjected to a predetermined pressure and also where economy of 30 production requires high speed of operation.

Heretofore it has been usual, in such situations, to employ a manually actuated pressure fluid valve and a pressure gage 35 to enable the operator to time the valve operation to reverse the press when such required pressure has been obtained. It has also been proposed to utilize as a source of power, pressure fluid intermittently supplied as by a pump, the pump being stopped 40 automatically when the pressure in the system builds up to a predetermined point. According to the present invention, the press having a valved connection to a source 45 of fluid maintained under pressure, such as an accumulator or other reservoir independent of the press operation, the valve is automatically actuated when the predetermined pressure within the press is reached, 50 opening the exhaust and reversing the press, discharging the formed article, feeding a fresh supply of material to the matrix, introducing again the pressure fluid, compressing the material until the required

degree of pressure is again reached, and 55 thus in cycle. The invention thus insures a uniform product and fully synchronized operation, without the employment of manual labor other than a general supervision of several such presses by a single 60 operator.

As an exemplary basis for the detailed description of the invention to follow, reference is had to the accompanying drawings in which—

Fig. 1 is a front elevation of a press embodying the invention;

Fig. 2 is a side view of the same;

Fig. 3 is a side view from the opposite 70 direction;

Fig. 4 is a longitudinal sectional view through the automatic valve employed;

Fig. 5 is an enlarged detail of the valve-actuating mechanism adjacent the valve; 75 and

Fig. 6 is a sectional plan view on the line 6—6 of Fig. 5.

Having more particular reference to Figs. 1, 2 and 3 of the drawings, the press is 80 shown as mounted upon a standard 11 and comprising, generally, a pressure cylinder 12 supplied with pressure fluid through the pipe 13, the cooperating piston 14, the cross head 15, the plunger die 16, the matrix 17, the pressure gage 18, fluid pressure control 85 valve 19, the piston 14 being retracted during the exhaust period by means of counter springs or pneumatic pressure device housed within the pillars 20 and acting through the cross head 15. The general press assemblage 90 thus far described is of known construction.

A feed hopper for the material to be acted upon is indicated at 21 provided in its lower portion with an agitator 22 by means of 95 which the material is discharged through the lower open end of the hopper into an open bottom carrier 23 having attached thereto at one end a cord 24 passing around a pulley 25 and counterweighted at 26; the carrier 23 near its center is connected by 100 means of a link 27 with one arm 28 of an angle lever pivoted at 29 the other arm of which 30 is provided with a bearing block 31 through which plays the rod 32 secured to the cross head 15 at 33, lock nuts 34 105 effecting an adjustable connection between the lever arm 30 and the rod 32.

By means of the mechanism last described,

it will be observed that as the die 16 and with it the cross-head 15 ascend after each pressure stroke the carrier 23, with its load of material, is moved from the position shown in Fig. 2 beneath the hopper to the position shown in Fig. 3 with its opened bottom portion 23^a above the matrix 17 and in line with the stroke of the plunger die 16. In this position the solid portion 23 of the carrier lies beneath the outlet from the hopper and closes the same. The material dropped from the pocket 23^a of the carrier falls into the matrix 17 and, as the plunger die 16 descends, the rod 32 travels downward relieving the arm 30 of the angle lever from engagement with the nut 34, permitting the counterweight 26 by means of the cord 24 to draw the carrier 23 to the left as shown in Fig. 3, or to the right 20 as shown in Fig. 2 to the position shown in the latter figure, with the pocket 23^a beneath the open end of the hopper, to receive another load of material. Continuing to descend, the cross-head 15 carries the rod 32 farther down causing the lock nut 34 to leave the bearing block 31, the die entering the matrix and compressing the material therein.

Mounted upon the cross-head 15 is a 30 spring catch 35 held in the position shown in Fig. 3 by means of a wedge pin 36, which pin 36 is held in adjusted position by means of the set screw 37. As the cross-head 15 descends, the catch 35 passes out of engagement with the wedge pin 36 and is caused by its spring 38 to snap into the notch 39 of the rod 40 which is at its lower end mounted in a bearing block 41 upon the arm 42 and the rock shaft 43 (Fig. 3), and upon 40 this rock shaft 43 is fixed another arm 44 (Figs. 1 and 2) the extremity of which bears beneath the lower end of an ejector rod 45 carrying at its upper end an ejector pin 46 headed at 47 to form the movable bottom 45 of the matrix 17.

When the plunger die 16 has compressed the material within the matrix 17 and begins its reverse stroke, the engagement of the catch 35 within the notch 39 of the rod 40 lifts the latter, rocking the arms 42 and 44 on the shaft 43 and lifting the ejector rod 45 and pin 46, discharging the formed article above the upper surface of the matrix in the path of the carrier 23 as the latter moves from the position shown in Fig. 2 to that shown in Fig. 3, the carrier wiping the formed article off the platen to any suitable point of discharge. The position of the wedge pin 36 is so adjusted as to retract 55 the catch 35 from the notch 39 at the instant the formed article reaches the level of the platen in front of the carrier, whereupon the rod 40 drops and with it the ejector pin 46 to the position shown in Fig. 1, ready 60 for the charging of the matrix with mate-

rial as the pocket 23 of the carrier again reaches a position over the matrix.

A description of the means whereby the movements of the press are accomplished is now in order: While in a fluid pressure press of this type various forms of control valves might be so modified as to embody the present invention, I have shown, for purposes of illustration, the invention as embodied in that form of high-pressure valve 70 patented on June 15, 1915 to me and numbered 1,143,236. The only material modification of that valve, is such as to enable it to be operated automatically by the press, under the control of built-up pressure therein, and to synchronize the operation of the valve precisely with that of the press. This valve, indicated generally at 19 in the drawings, is shown in detail in Fig. 4.

The inlet of pressure fluid to the valve 85 casing 19 is through the supply pipe 48 and the exhaust at 49, while the port for supply of pressure fluid to the press or the return therefrom to the exhaust is shown at 50. The bore of the casing 19 between the inlet 90 48 and the supply port 50 has an apertured partition 51 forming a guide and seat for the inlet controlling valve 52 which valve is guided in the plug 53 and acted upon by the compression spring 54 tending to maintain the same in closed position. The portion of the bore of the casing between the port 50 and the exhaust 49 is restricted to form a shoulder 55 and disposed in this portion of the bore is a guiding sleeve 56 bearing upon a packing 57 positioned between the sleeve and shoulder. Slidably mounted in the sleeve and adapted to be brought into engagement with the valve 52 is a floating piston-plug 58 having a bore 59 extending therethrough and adapted to place the port 50 in fluid communication with the outlet or exhaust 49. The sleeve 56 provides a shoulder at 60 forming a stop for the upward movement of the piston 58. Slidably mounted within the sleeve 56 above the piston 58 is a rod 61 pivoted at its upper end to toggle links 62, 63, the link 63 being pivoted at 64 to the cross bars 65 of a yoke the side members 66 of which rigidly upstand from the valve casing. A lever 67 is fulcrumed at 68 in the said yoke and from its pivot pin extends at right angles an arm 69 connected by a link 70 to the breaking point of the toggle at 71. One arm of the lever 67 is counterweighted at 72 and has pivoted thereto at 73 a rod 74 which extends upwardly alongside the press and is hooked over in apertured engagement at 75 with a stationary rod 76 adjustably mounted on the press by a set collar 77. This rod 76 carries a collar 78 forming the lower abutment for a compression spring 79 and having an extension 80 for adjustably holding by means of the set screw 81 a tappet 82.

The compression spring 79 surrounds the rod 76 and underlies the overturned end 75 of the rod 74. The pivoted dog 83 counterweighted at 84 rests normally under the influence of the counterweighted end with a hooked portion against the side of a plate 85 mounted on the rod 74, and is adapted upon the descent of the rod 74 to take over the upper edge of the plate 85 and hold it in a depressed condition until released by the tappet pin 82 as will be hereafter described. The press-supply pipe 50 leading from the valve terminates in a coupling 86 one branch of which connects with the fluid pressure supply pipe 13 and another branch to a pipe 87, elbow 88, and riser pipe 89 the upper end of which pipe 89 is provided with a blow-off or pop-valve 90 which is normally controlled by the weighted restraining arm 91 pivoted at 92 to the bracket 93 and counterweighted at 94, this counterweight being adjustable in order to vary the pressure holding the pop-valve 90 closed. A link rod 95 pivoted at 96 to the lever arm 91 is slidable at its lower end in the tail 97 of a dog 98 the lower beveled hooked end of which is adapted to engage over a stud 99 carried by the lever arm 67. When it is desired to start the press which is standing idle the operator bears down upon the lever 67 (Fig. 5) straightening the toggle 62-63 and bringing the stud 99 into engagement with the dog 98 whereby it is held in this elevated position. The plunger rod 61 is thus caused to bear downward upon the floating piston 48 opening the inlet valve 52 and permitting the pressure fluid to flow from the accumulator or reservoir by way of the pipe 48 through the valve to the supply port 50 and thence through the pressure supply pipe 13 to the press cylinder above the piston and likewise through the pipes 87-89 to a point below the pop-valve 90. This causes the piston 14, the cross head 15 and the plunger die 16 to descend, the descent of the rod 32 permitting the angle lever 28-29 to give and the counterweight 26 by means of the cord 27 to draw the shuttle carrier into position for a new supply of material as shown in Fig. 2. The open connection between the inlet pipe 48 through the valve to the press-supply pipe 50 permits the pressure to build up within the cylinder above the piston, said pressure being visually indicated by the gauge 18 connected with the supply pipe 13, until that predetermined pressure is attained for which the pop-valve is set by the adjustment of the weight 94. As soon as this pressure is obtained within the cylinder and upon material within the matrix 17, the pop valve 90 rises, lifting the lever arm 91, and disconnecting by means of the rod 95 the dog 98 from the stud 99, permitting the lever 67 counterweighted at 72 to drop, breaking the toggle 62-63 as shown in Fig. 5 and lifting the plunger-rod 61, thus permitting the valve 52 to close and shut off the supply of pressure fluid from the pipe 48, the back pressure at 50 lifting the floating piston 58 but leaving a passage through the port 59 at the valve seat 60 with the exhaust 49. A communication being thus established between the cylinder space above the piston and the exhaust, the piston 14, the cross head 15 and the plunger die 16 are raised by means of the spring or pneumatic devices within the pillars 20. Simultaneously, the rod 40 is lifted by its engagement with the catch 35 and the ejector pin 46 lifts the formed article to the upper level of the press platen while the rod 32 rocks the shaft 29, moving the carrier 23 across the matrix to sweep the formed article therefrom and to discharge a new load of material into the matrix. At the same moment, the wedge pin 36 disengages the catch 35 from the rod 40 and permits the ejector pin to drop. As the piston of the press reaches its uppermost position, the cross head 15 by means of its guiding collar 100 carries upwardly the set collar 77 attached to the rod 76, thus lifting the rod 76 and strongly compressing the spring 79 beneath the overturned end 75 of the rod 74. This continues until the tappet 82 strikes the tail 84 of the dog releasing the hook 83 from the plate 85, whereupon the compressed spring 79 reacts to force the rod 74 upward, lifting the weighted end of the lever 67 and effecting again an engagement between its stud 99 and the dog 98, thereby breaking the toggle 62-63, depressing the plunger rod 61 closing the communication between the press supply port 50 and the exhaust and again opening a communication between the inlet pipe 48 and the said press supply port 50, and thus in cycle. It will thus be observed that whether the press acts more slowly or more rapidly, dependent upon the pressure fluid supply, the valve will not be shifted to reverse the movement of the press until the pressure within the press cylinder and consequently upon the article being formed has built up to the required degree, as predetermined by the adjustment of the weight 94 upon the lever 91 controlling the pop-valve 90; that as soon as such predetermined pressure is reached, the valve acts automatically and quickly without the intervention of any operative to reverse the press, to discharge the formed article to supply to the matrix other material, and to again reverse the action of the press to effect the forming of another article. There is thus attained a precise synchronizing of the valve and the press regardless of variations in speed of operation and also a control of the valve actuation by means of the conditions present in the press as determined.

fined in terms of pressure upon the articles being formed. A single operative can supervise the operation of a battery of presses all of which, having once been set in motion, continue to function with precision and without farther attention. All that is required to stop the operation of a press, at the end of a job or to effect adjustment, is to move the lever 67 momentarily to an intermediate position, whereby to establish communication for the time being directly between the inlet port of the valve and the exhaust.

As previously intimated, it will now be obvious that the invention is susceptible of embodiment in connection with various types of presses and valves, and such necessary modification of constructional details and assemblage as will readily suggest themselves to persons skilled in the art under changed conditions, all without material departure from the invention as set out in connection with this preferred embodiment. It will be seen therefore that this detailed description and drawings upon which it is predicated are to be taken in an illustrative and not in an unnecessarily limiting sense.

I claim:

1. The combination with a continuous pressure fluid operated press, and a control valve therefor, of a connection between the press and valve whereby to synchronize the operation of the press and valve under all variations in speed of press operation.

2. The combination with a continuous pressure fluid operated press, and a control valve therefor comprising inlet, press and exhaust ports and a valve plug to connect the press port alternatively with the supply and exhaust, of a connection between the press and valve whereby to synchronize the operation of the press and valve under all variations in speed of press operation.

3. The combination with a pressure fluid operated press, and a control valve therefor comprising inlet, press and exhaust ports and a valve plug to connect the press port alternatively with the supply and exhaust, of a connection between the press and valve whereby to synchronize the operation of the press and valve under all variations in speed of press operation, said connection comprising mechanism for shifting the valve plug, an actuating rod therefor, gravitational means for moving the rod in the direction of press reversal, a detent to hold the rod in reversal position, a spring bearing on the rod in a direction opposed to gravity, an abutment for the spring disposed in the path of a moving part of the press whereby to compress the spring as the press reverses, a tappet actuated by the movement of the press near its reverse limit to disengage the detent, whereby the stressed spring there-

upon effects the movement of the actuating rod against gravity to shift the valve plug and start the press in its work stroke and as the spring abutment is relieved from the action of the press the unstressed spring permits gravity to move the actuating rod in the opposite direction to shift the valve plug and again reverse the press.

4. The combination with a continuous pressure fluid operated press, and a pressure fluid control valve, of means under the control of the head of pressure in the press to actuate the valve whereby the valve will be automatically timed to reverse the press when the pressure exerted thereby reaches a predetermined degree.

5. The combination with a continuous pressure fluid operated press, and a control valve therefor comprising inlet, press and exhaust ports and a valve plug to connect the press port alternatively with the supply and exhaust, of means under the control of the head of pressure in the press to actuate the valve whereby the valve will be automatically actuated to connect the press with the exhaust port and to reverse the press when the pressure exerted thereby reaches a predetermined degree.

6. The combination with a continuous pressure fluid operated press, and a control valve therefor comprising inlet, press and exhaust ports and a valve plug to connect the press port alternatively with the supply and exhaust, of means under the control of the head of pressure in the press to actuate the valve whereby the valve will be automatically actuated to connect the press with the exhaust port and to reverse the press when the pressure exerted thereby reaches a predetermined degree, said means comprising a movable member subject to the pressure within the press, yielding restraining means tending to hold the said member stationary, and a connection between the restraining means and the valve plug whereby when the said member is moved by built up pressure within the press the valve plug will be moved to connect the press with the exhaust port.

7. The combination with a pressure fluid operated press, and a control valve therefor comprising inlet, press and exhaust ports and a valve plug to connect the press port alternatively with the supply and exhaust, of means under the control of the head of pressure in the press to actuate the valve whereby the valve will be automatically actuated to connect the press with the exhaust port and to reverse the press when the pressure exerted thereby reaches a predetermined degree, said means comprising a pop-valve subject to the pressure within the press, regulable yielding restraining means tending to hold the pop-valve seated, and a

connection between the restraining means and the valve plug whereby when the pop-valve is unseated by built-up pressure within the press the valve plug will be moved to 5 connect the press with the exhaust port.

8. The combination with a pressure fluid operated press, and a control valve therefor comprising inlet, press and exhaust ports and a valve plug to connect the press port alternatively with the supply and exhaust, 10 of means under the control of the head of pressure in the press to actuate the valve whereby the valve will be automatically actuated to connect the press with the exhaust 15 port and to reverse the press when the pressure exerted thereby reaches a predetermined degree, said means comprising a pop-valve subject to the pressure within the press, a restraining lever fulcrumed on the 20 pop-valve to hold it seated, a shiftable weight on the lever to vary the action on the pop-valve, and a connection between the restraining lever and valve plug whereby when the pop-valve is unseated by built-up 25 pressure within the press the valve plug will be moved to connect the press with the exhaust port and reverse the movement of the press.

9. The combination with a pressure fluid 30 operated press, and a control valve therefor comprising inlet, press and exhaust ports and a valve plug to connect the press port alternatively with the supply and exhaust, of means under the control of the head of pressure in the press to actuate the valve whereby the valve will be automatically actuated to connect the press with the exhaust port and to reverse the press when the pressure exerted thereby reaches a predetermined 35 degree, said means comprising a pop-valve subject to the pressure within the press, a restraining lever fulcrumed on the pop-valve to hold it seated, a shiftable weight on the lever to vary the action on the pop-valve, a toggle arranged when straightened to hold the valve plug in position to maintain the press in communication with the inlet port and not with the exhaust port and when broken to shift the valve 40 plug to close the inlet port and connect the press with the exhaust port, and a connection between the toggle and restraining lever whereby when the pop-valve is unseated the toggle will be broken.

10. The combination with a continuous 45 pressure fluid operated press, and a control valve therefor comprising inlet, press and exhaust ports and a valve plug to connect the press port alternatively with the supply and exhaust, of a connection between the press and valve whereby to synchronize the operation of the press and valve under all variations in press operation and to reverse the press when the pressure exerted thereby reaches a predetermined degree.

11. The combination with a pressure fluid operated press, and a control valve therefor comprising inlet, press and exhaust ports and a valve plug to connect the press port alternatively with the supply and exhaust, 70 of a connection between the press and valve whereby to synchronize the operation of the press and valve under all variations in press operation and to reverse the press when the pressure exerted thereby reaches a predetermined degree, said means comprising valve plug shifting mechanism, an actuating rod therefor, a movable member subject to the pressure within the press, yielding restraining means tending to hold the said member stationary, a connection between the restraining means and the valve-actuating rod, said connection being a releasable one whereby upon the movement of the member 75 acted upon by the pressure within the valve in opposition to its restraining means the actuating rod will be moved to a position for reversing the press, a detent carried by the press to hold the rod in reversal position and to lift the rod as the press nears the limit of its reversal stroke to effect reconnection of the actuating rod with the restraining means, and a tappet actuated at the limit of the reversal movement of the press to release the detent whereby to permit the release of the connection between the actuating rod and the restraining member when the pressure within the press builds up to the predetermined degree.

12. The combination with a pressure fluid operated press, and a control valve therefor comprising inlet, press and exhaust ports and a valve plug to connect the press port alternatively with the supply and exhaust, 95 of a connection between the press and valve whereby to synchronize the operation of the press and valve under all variations in press operation and to reverse the press when the pressure exerted thereby reaches a predetermined degree, said connecting mechanism comprising a pop-valve subject to the pressure within the press, a restraining lever fulcrumed on the pop-valve to hold it seated, a shiftable weight on the lever to vary the action on the pop-valve, a toggle arranged when straightened to hold the valve plug in position to maintain the press in communication with the inlet port and not with the exhaust port and when broken to shift the valve plug to close the inlet port and connect the press with the exhaust port, a weighted lever tending by gravity to break the toggle, a releasable connection between the toggle lever and restraining lever whereby when the pop-valve is unseated the toggle will be broken and the control valve shifted to effect communication between the press and the exhaust port and to reverse the press when the pressure exerted thereby reaches a degree predetermined by the ad- 100 105 110 115 120 125 130

justment of the weight on the restraining lever, a valve-actuating rod connected with the restraining lever and tending by the gravitational action thereof to move to a position of reversal, a spring bearing on the rod in a direction opposed to gravity, an abutment for the spring disposed in the path of a moving part of the press whereby to compress the spring as the press reverses, a 10 detent to hold the rod in reverse position, a tappet actuated by the movement of the press near its reverse limit to disengage the detent whereby the stressed spring thereupon effects movement of the actuating rod 15 against gravity to shift the valve plug and start the press on its work stroke and as the spring abutment is relieved from the action of the press the unstressed spring permits gravity to move the actuating rod in the opposite direction to shift the valve plug and again reverse the press, the action of the stressed spring being to again connect the released connection between the toggle operating lever and the weighted restraining lever.

25 13. In a press, the combination of a movable die, a cooperating matrix, means to operate the press, a hopper for the material to be compressed, a shuttle carrier mounted to move between the hopper and matrix, yielding means to move the empty carrier from the matrix to the hopper, and mechanical means synchronized with the movement of the press to move the loaded carrier from the hopper to the matrix.

30 14. In a press, the combination of a movable die, a cooperating matrix, means to operate the press, a hopper for the material to be compressed, a shuttle carrier mounted to move between the hopper and matrix, yielding means to move the empty carrier from the matrix to the hopper, and mechanical means synchronized with the movement of the press to move the loaded carrier from the hopper to the matrix and to eject the 45 formed article from the matrix.

50 15. In a press, the combination of a movable die, a cooperating matrix, means to operate the press, a hopper for the material to be compressed, a shuttle carrier mounted to move between the hopper and matrix, yielding means to move the empty carrier from the matrix to the hopper, and mechanical means synchronized with the movement of the press to move the loaded carrier from the hopper to the matrix, said last named 55 means comprising a rock arm linked to the carrier, an arm-actuating rod connected at one end to a moving part of the press and at the other end to the arm whereby as the 60 press moves in its work stroke the yielding carrier-moving means will be unrestrained and as the press moves in its reverse stroke the rock arm will be actuated to move the carrier in opposition to the yielding means.

65 16. In a press, the combination of a mov-

able die, a cooperating matrix, means to operate the press, a hopper for the material to be compressed, a shuttle carrier mounted to move between the hopper and matrix, yielding means to move the empty carrier from the matrix to the hopper, and mechanical means synchronized with the movement of the press to move the loaded carrier from the hopper to the matrix, said last named means comprising an arm linked to the carrier, an arm-actuating rod connected to a moving part of the press at one end and at the other end to the arm, one point of connection being fixed and the other a sliding connection permitting a relative movement in one direction only, whereby as the press moves in its work stroke the yielding carrier moving means will be unrestrained and as the press moves in its reverse stroke the rock arm will be actuated to move the carrier in opposition to the yielding means.

70 17. In a press, the combination of a movable die, a cooperating matrix, means to operate the press, a hopper for the material to be compressed, a shuttle carrier mounted to move between the hopper and matrix, yielding means to move the empty carrier from the matrix to the hopper, and mechanical means synchronized with the movement of the press to move the loaded carrier from the hopper to the matrix, the last mentioned means comprising a rock arm linked to the carrier, an arm-actuating rod fixed at its upper end to a moving part of the press and at its lower end to the arm, the point of connection to the press being fixed and the connection to the arm having a relative movement in one direction only whereby as the press moves in its work stroke the yielding carrier moving means will be unrestrained and as the press moves in its reverse stroke the rock arm will be actuated to move the carrier in opposition to the yielding means.

75 18. In a press, the combination of a movable die, a cooperating matrix, means to operate the press, a hopper for the material to be compressed, and means for charging the matrix from the hopper, of means to eject the formed article from the matrix comprising an ejector entering the matrix from below, an actuating rod connected to the ejector and acted upon by a moving part of the press in its reverse stroke to operate the ejector to discharge formed articles from the matrix.

80 19. In a press, the combination of a movable die, a cooperating matrix, means to operate the press, a hopper for the material to be compressed, and means for charging the matrix from the hopper, of means to eject the formed article from the matrix comprising an ejector having a head forming the bottom of the matrix, an arm carrying said ejector, an actuating rod connected to the ejector arm and acted upon by a moving

part of the press in its reverse stroke to operate the ejector to discharge the formed article from the matrix.

20. In a press, the combination of a movable die, a cooperating matrix, means to operate the press, a hopper for the material to be compressed, and means for charging the matrix from the hopper, of means to eject the formed article from the matrix comprising an ejector having a head forming the bottom of the matrix, an arm carrying said ejector, an actuating rod connected to the ejector arm, a detent moving with the press and arranged to engage with the actuating rod in the direction of actuation for the ejector, and a detent trip arranged to release the actuating rod upon the completion of the act of ejection.

21. The combination with a continuous pressure fluid operated press, and a control valve therefor comprising inlet, press and exhaust ports and a means to connect the press port alternatively with the supply and exhaust, of a connection between the press and valve whereby to synchronize the operation of the press and valve under all variations in speed of press operations.

22. The combination with a continuous

pressure fluid operated press, and a pressure fluid control valve, of means under the control of the head of pressure in the press to actuate the valve whereby the valve will be automatically timed to reverse the press movement immediately when the pressure exerted thereby reaches a predetermined degree.

23. The combination with a continuous pressure fluid operated press, and a control valve therefor comprising inlet, press and exhaust ports and means to connect the press port alternatively with the supply and exhaust, of means under the control of the head of pressure in the press to actuate the valve whereby the valve will be automatically actuated to connect the press with the exhaust port and to reverse the press when the pressure exerted thereby reaches a predetermined degree.

In testimony whereof I have hereunto signed my name in the presence of two subscribing witnesses.

HARVEY SLATER.
